UNITED STATES PATENT OFFICE.

ALONSO CARDOSO DE LOS RIOS, OF HABANA, CUBA.

PROPELLER.

1,031,629.

Specification of Letters Patent.

Patented July 2, 1912.

Application filed May 11, 1911. Serial No. 626,469.

To all whom it may concern:

Be it known that I, ALONSO CARDOSO DE LOS RIOS, a subject of the King of Spain, and a resident of Habana, Cuba, have invented a new and Improved Propeller, of which the following is a full, clear, and exact description.

This invention relates to propellers for different purposes, and has reference more particularly to a propeller comprising an elongated, tapered hub, and an elongated, tapered screw blade, that is to say, a blade of varying radius.

The object of the invention is to provide a simple, strong and efficient propeller which can be employed for purposes of propulsion in connection with marine vessels, aeroplanes, and for other purposes, which provides an increased driving surface over the ordinary propeller, by means of which negative slip can be minimized, which may be of any desired pitch, measured both radially and longitudinally, which may be of sectional form to facilitate repair and replacement, and which may be fashioned from any suitable material.

The invention consists in the construction and combination of parts to be more fully described hereinafter and particularly set forth in the claims.

Reference is to be had to the accompanying drawings forming a part of this specification, in which similar characters of reference indicate corresponding parts in all the views, and in which—

Figure 1 is a side elevation of an embodiment of my invention; Fig. 2 is a longitudinal section of the propeller; and Fig. 3 is a transverse section on the line 3—3 of Fig. 2.

Before proceeding to a more detailed explanation of my invention, it should be clearly understood that while the same is particularly useful as a propeller for marine propulsion, it can also be advantageously applied to other uses, for example, as a propeller for aeroplanes or other types of airships. If so desired, the device can also be adapted for different purposes in which screw blades are employed, for example in connection with air-forcing mechanism or the like.

Certain of the details of construction shown for example herewith, form no part of the invention, and can be varied in accordance with individual preference and

special conditions, without deviating from the essence of the invention as defined in the appended claims.

Referring more particularly to the drawings, I have shown for example, a shaft 9 of conventional form, upon which the propeller is mounted. The propeller illustrated herewith is formed in three sections A, B and C, which have hollow hubs 10, 11 and 12 respectively, of elongated, tapered form. The hubs 10 and 11 at corresponding ends have reduced, threaded necks 13 and 14 adapted to be received in the correspondingly threaded ends of the respective sections 11 and 12, to assemble the sections and to form a continuous, elongated, tapered hub. At the opposite ends, the sections 10 and 12 are internally threaded, and receive respectively, reduced, threaded parts of heads 15 and 16, of suitable form. The heads engage the annular end edges of the sections 10 and 12 and are provided with openings 17 and 18 through which the shaft 9 extends.

The propeller has blades of tapered, helical form. That is to say, the blades have helical surfaces of any suitable pitch and if desired, of varying pitch, and of varying radius. The blades are sectional, and each of the sections A, B and C has corresponding blade sections 19, 20 and 21 associated therewith. While I have shown for example herewith blade and hub sections formed integral, the blade sections may be associated removably in any suitable manner with the hubs, if so desired. Any suitable number of blades may be employed, though I prefer to use three as illustrated. The sections of the propeller are so assembled that the respective blade sections register, so that the blades are continuous from one end of the hub to the other. I prefer to extend the ends of the blade sections 19 and 21 longitudinally beyond the corresponding ends of the hub sections 10 and 12, as is clearly shown in Fig. 1. These ends are preferably rounded.

It will be understood that certain of the considerations which apply to ordinary propellers also apply to my propeller. For example, considerations of different pitch, blade area, driving surface, blade edge form, and materials of construction. As is shown herewith, I prefer to employ blades in which the longitudinal pitch decreases toward the smaller end of the hub. Owing to the ta-

2
pered form of the blades the line of the free edge of each blade is substantially a conical spiral.

Having thus described my invention, I claim as new, and desire to secure by Letters Patent:

1. A propeller, comprising a plurality of sections, each consisting of an elongated, tapered hub and a helical blade section, certain of said hub sections having threaded engagement, and heads having threaded engagement with the end hub sections, the lines of the free edges of said blades being substantially conical spirals.
- 15 2. A propeller comprising a plurality of

sections, each consisting of an elongated, tapered hub and a helical blade section, one of said hub sections having a reduced, threaded end, the other of said hub sections being interiorly threaded to receive said reduced end, the lines of the free edges of said blades being substantially conical spirals. 20

In testimony whereof I have signed my name to this specification in the presence of two subscribing witnesses.

ALONSO CARDOSO DE LOS RIOS.
